UNITED STATES PATENT OFFICE.

ARTHUR SPEAR, OF CHICAGO, ILLINOIS, ASSIGNOR TO MILLS NOVELTY COMPANY, OF CHICAGO, ILLINOIS, A CORPORATION OF ILLINOIS.

COIN-OPERATED VENDING-MACHINE.

No. 836,346.

Specification of Letters Patent.

Patented Nov. 20, 1906.

Application filed April 17, 1905. Serial No. 255,936.

To all whom it may concern:

Be it known that I, ARTHUR SPEAR, a citizen of the United States, residing at Chicago, in the county of Cook and State of Illinois, 5 have invented a new and useful Improvement in Coin-Operated Vending-Machines, of which the following is a specification.

My invention relates to an improvement in the class of machine adapted for vending 10 small articles—such as envelops, pieces or packages of gum, and the like—from a pile thereof housed in the machine and from the base of which delivery is effected by means requiring for its accomplishment the use of a 15 coin of the denomination representing the purchase price of the article to be delivered by its use.

The invention relates particularly to the construction of the coin-controlled delivery 20 mechanism of a machine in the class referred to, my object being to provide a novel construction of such delivery mechanism which shall be simple to manufacture, without liability to get out of order by use, and which 25 shall be compact, with its parts so close as to leave no room for introducing between or through them into the machine wires or other unwarrantable means in attempts to cheat the machine by operating it without the use of 30 a proper coin for the purpose.

Referring to the accompanying drawings, Figure 1 is a vertical sectional view of a vending-machine provided with my improved coin-controlled delivery mechanism. Fig. 2 35 is a longitudinal sectional view like and in the withdrawn condition of the representation thereof in Fig. 1, but drawn to a larger scale; Fig. 3, a similar view of the same with the slide forced inward to the possible limit 40 without the use of a coin; Fig. 4, a view like that presented by Fig. 3 with the parts in the same relative positions, but having a coin inserted to permit further inward movement of the slide; Fig. 5, a similar view showing 45 the slide in its innermost coin-actuated position with the coin being dislodged, and Fig. 6 illustrating the several parts of the delivery mechanism in perspective in the relative positions of assembling them.

50 The delivery mechanism comprises as its preferred construction in matters of detail the following-described parts:

A is the thin metal base-plate of general rectangular form shown to be provided near

its forward end with a rectangular slot *a* narrower than a coin *C* proper for use and flanked by slotted ears *b*, the slot *a* terminating in a rounded extension *a'* of greater diameter than the coin, and beyond the extension *a'* is provided centrally in the base-plate a narrow elongated slot *c*, the plate terminating at its rear end in an upright flange *d*, through which to fasten it in place, as hereinafter described.

B is the slide-plate, of the same general shape as the plate A, upon which it is confinedly supported to adapt it to be reciprocated. The slide-plate is provided with an upturned flange *e*, affording a handle, on its forward end, and contains a circular coin-recess *f*, shown with a forward extension *f'*, and an elongated slot *g*, into which fits an abutment-plate *h*, forming a section of the slide-plate and containing a forward short slot or opening *h'* and a rear elongated slot *h''* 75 and having a post *i* rising from its rear end and carrying a delivery-plate *k*, flanged at *k'*, along its rear edge.

The parts thus described are assembled with the slide-plate B on the base-plate A and 80 the abutment-plate reciprocably confined in the slot *g* and supported on the base-plate, and the base-plate and slide-plate are secured together by a yoke-plate D, provided on each edge with a depending tongue, like 85 that represented at *l* in Fig. 6, to enter a slot in an ear *b*, wherein it is fastened by upsetting it, thus straddling the plate B and confining it reciprocatingly in place. The abutment-plate is similarly confined in the slot *g* by a screw 90 *m*, provided with a washer *m'* and passing through the base-plate slot *c* into the base of the post *i*. The yoke-plate is provided with a central aperture *n*, and has fastened upon its face by a screw *o* one end of a spring-pawl *E*, 95 bent near its center to form a shoulder *p*, registering and projecting into the aperture *n* and provided on its free end with a stop *q*, registering with an opening *r* in the yoke-plate. 100

F is the casing of the machine, having a base-chamber *F'*, from the top of which rises the receptacle *F''* for the articles to be vended and of the proper shape for a pile of the particular articles—in this instance shown as envelops *G*—resting on the top of the casing-chamber and surmounted by a flat compacting weight *H*. 105

The front of the receptacle may be glass I, and its back K is removable and provided with a lock (indicated at t) for permitting access to the chamber F' only by an authorized 5 person possessing a key to fit the lock. A false back K' is also provided to avoid liability to disturbing the contents of the receptacle each time the chamber F' is opened to gather the coins that enter it in operating 10 the machine by removing the back K. The false back is also removable to permit access to the receptacle for replenishing it from time to time.

The casing-base forms at the front of the receptacle F², at its junction therewith, a ledge L and a delivery-slot s for the lowermost article G in the pile thereof, the delivery of which is effected in the manner hereinafter described.

With the parts of the delivery mechanism 20 assembled it is supported in the upper part of the chamber F', the plate A being fastened at its flange d to the back of the top u of the chamber containing an opening u' and the plates A and B passing at their forward ends 25 through a slot v in the forward wall of the chamber and through a slotted metal plate w, secured on the face of the wall to cover the slot.

As will be observed, the flat metal parts of 30 the delivery mechanism as assembled render it very compact and thin, leaving no openings through which to insert wires, toothpicks, and other means commonly resorted to by dishonest persons for insertion into the machine in attempts to work it without using a 35 coin to effect the delivery of a vendable article from the casing, and the slot or opening in the casing through which the plates A and B pass at their forward ends is fitted by them 40 so closely as to leave no opening past them through which to introduce such prohibited means.

To actuate the delivery mechanism, the procedure is as follows: With the slide-plate 45 B in its drawn-out position, in which it is represented in Figs. 1 and 2, a copper cent or other coin for which the machine is adapted and representing the purchase price of an article to be delivered is inserted into the recess f to rest upon the plate A, whereupon 50 the slide-plate by manipulating it at its handle e is forced inward, thereby passing the coin along the slot a in the base-plate, which is narrower than the coin, so that the latter 55 remains confined between the edges of that slot and the under side of the yoke-plate D. When the coin being thus carried by the backward movement of the slide-plate is brought under the opening n in the yoke-plate, it raises out of the latter the shoulder p 60 of the spring-pawl E, and thereby also raises the stop-tooth q on the free end of the pawl out of the slot h² in the abutment-plate h, keeping the spring-pawl thus raised, as represented in Fig. 4, until the coin in the further 65

movement of the slide-plate clears the shoulder p, in doing which it enters the enlargement a' of the slot a, which is of greater diameter than the coin, thus permitting the latter to drop out of the delivery mechanism 70 into the coin-receiving chamber F'. In this last-attained position of the coin the shoulder p under the recoil action of the spring-pawl again enters the aperture n, thereby entering the tooth q through the aperture r against 75 the top of the coin with the effect of dislodging it, as represented in Fig. 5, in the event of its sticking, the parts being then in the relative positions in which they are shown in Fig. 5. The slide-plate has thus been forced inward to the fullest possible extent to bring the flange k' of the delivery-plate k, on which the envelops G rest, behind the rear edge of the lowermost envelop in the pile thereof, the flange entering a recess x, Fig. 1, in the back 80 K' to insure its clearing the rearmost edge of the lower envelop. Thereupon the operator pulls out the slide-plate, and by so doing the flange k' engages and pushes ahead of it the lowermost envelop through the slot s upon 85 the ledge L, thus effecting its delivery to the purchaser who removes it.

Unless a coin is placed in the recess f preliminary to pushing in the slide-plate no delivery will be effected, since without the coin 90 the delivery-plate will not be forced backward far enough to cause its flange to clear the rear edge of the lowermost envelop. The inward movement of the slide-plate will engage it with the forward end of the abutment-plate h and force the latter backward across the shoulder p (thus momentarily but impotently raising the spring-pawl E) until the forward end of the slot h² in the abutment-plate 95 encounters the stop-tooth q, the parts 100 being then in the relative positions in which they are represented in Fig. 3. This encounter locks the abutment-plate, and therefore also the slide-plate, against further backward movement, the extent of which has been only 105 sufficient to bring the flange k' of the delivery-plate underneath the package of envelops, so that when the slide-plate is again drawn out the delivery-plate will move under the package without producing any delivery. 110

The slot h' in the forward end of the abutment-plate is especially provided to prevent the machine from being operated by the use of an annular disk, such as a washer. 115 When a washer is inserted into the recess f in lieu of the proper coin, inward movement of the slide-plate brings the washer into engagement with the shoulder p and raises the spring E accordingly; but when the central opening in the washer registers with the opening n the recoil of the spring passes the tooth q through the slot h', thereby locking the slide-plate B against the required extent of inward movement. 120

If for any reason it is desired after inserting a coin into its recess *f* and before pushing inward the slide-bar to withdraw the coin, it is accessible for the purpose of dislodging it 5 from the recess, in which it fits closely, through the extension *f'*.

As the slotted abutment-plate *h* is reciprocably confined in a longer slot in the slide-plate *B*, enough lost motion is afforded to the 10 abutment-plate to avoid the necessity of forcing the slide-plate to its full inward limit to bring the delivery-plate *k* behind shorter or broken pieces of the articles to be vended, such as gum, that may be contained in the 15 stack thereof in the magazine holding the supply of such articles.

What I claim as new, and desire to secure by Letters Patent, is—

1. Coin-controlled delivery mechanism for 20 a vending-machine, comprising, in combination, a slotted base-plate, a slide-plate reciprocably supported thereon and provided with a coin-recess, an abutment-section of said slide-plate containing a forward opening and 25 a rear elongated slot and carrying a delivery device, a yoke-plate provided with openings and fastened to said base-plate to confine thereon said slide-plate, and a spring-pawl secured on said yoke-plate and provided with 30 a stop on its free end to engage said abutment-

section at the slot therein through one of said yoke-plate openings, and provided between its ends with a shoulder extending through the outer yoke-plate opening into the path of the coin in said recess, to be engaged thereby, 35 for the purpose set forth.

2. Coin-controlled delivery mechanism for a vending-machine, comprising, in combination, a slotted base-plate, a slide-plate containing a coin-recess and a longitudinal slot, 40 a yoke-plate provided with openings and reciprocably confining the slide-plate on the base-plate, an abutment-plate having a forward opening and a longitudinal slot in rear thereof and carrying a delivery device, said 45 abutment-plate being confined in the slot in said slide-plate, and a spring-pawl secured on said yoke-plate, provided with a stop on its free end to engage the abutment-plate at the slot therein through one of said openings in 50 the yoke-plate, and between its ends with a shoulder extending through the other opening in the yoke-plate into the path of a coin in said recess, to be engaged thereby, for the purpose set forth.

ARTHUR SPEAR.
